UNITED STATES PATENT OFFICE

SAMUEL N. COULTER, OF LOS ANGELES, CALIFORNIA

GARMENT SUPPORTER

Application filed January 18, 1930. Serial No. 421,760.

This invention relates to garment supporters and while features of the invention adapt the improvement for use with garment supporters or suspenders of different types, the invention is especially applicable in the construction of garters. It has been the practice to construct a man's garter with an encircling band of elastic webbing or rubber. When so constructed, the entire band is constantly in tension when the garter is worn and the elastic quality of the band gradually diminishes, finally rendering the garter useless. It has been attempted to construct men's garters of an unelastic, substantially unextensible material such as a broad band of leather. These garters perform their function fairly well but, due to the fact that they have no elasticity, when worn they tend to work further and further down on one's calf, eventually becoming so tight as to prevent proper circulation and so as to become uncomfortable.

One of the reasons why the elastic band loses its elasticity so rapidly is that there is no limit to the amount of stretching to which the garter band may be subjected.

The general object of this invention is to produce a garter which will overcome these difficulties.

A further object of the invention is to provide a garter having a construction which will develop forces in the garter tending to prevent the same from sagging down on one's calf, as suggested above, and also constructed in such a way as to maintain the elasticity in the garter.

A further object of the invention is to provide a garment supporter carrying an elastic member that can readily be renewed when its elasticity has become lost, thereby avoiding the necessity for throwing away the whole supporter.

A further object of the invention is to provide a garter having a construction which will give it sufficient elasticity and adjustability but constructed in such a way as to limit the stretching of the elastic or resilient member.

Further objects of the invention will appear hereinafter.

The invention consists in the novel parts

and combinations of parts to be described hereinafter, all of which contribute to produce an efficient garter.

A preferred embodiment of the invention is described in the following specification, while the broad scope of the invention is pointed out in the appended claims.

In the drawings:

Figure 1 is a perspective of a garter embodying my invention. This figure illustrates a man's garter and represents a portion of the leg carrying it.

Figure 2 is a longitudinal section through another embodiment of my garter, and extending from one side of the pad to the loose end of the band, and further illustrating details of the invention.

Figure 3 is a front elevation upon a larger scale, illustrating a portion of the garter illustrated in Fig. 2 with certain parts broken away.

Figure 4 is a perspective illustrating the resilient or elastic tension member of the garter removed from the band.

Figure 5 is a side elevation showing a garter of another type embodying the invention and illustrating how the invention can be applied to a lady's garter as well as to a man's garter.

Referring more particularly to the parts, 1 represents a garter embodying my invention, which may comprise the usual pad or pads 2 carrying fasteners 3 to be attached to the upper edge of the hose 4.

This garter includes a band 5 one end of which is attached to one of the pads 2 and the other end of which carries a detachable fastening member 6 to be attached to a detachable fastening member 7 on the other side of the other pad 2. This band 5 is provided with means enabling a portion of it to be covered by a tension member 8, it being understood that the band itself is of substantially unextensible material such as cloth webbing, light leather or similar material. The garter is constructed in such a way that when the tension member 8 is applied to the garter, a portion 9 of the band which is overlain by the tension member 8 will be in a slack condition, that is to say, this portion 9

of the band is slightly longer than the tension member 8 when in its unextended condition. With this arrangement it will be evident that when the tension comes on the 5 garter band, the overlain portion 9 will limit the amount of extension of the tension member 8. When a garter having this feature of construction is in use, it will be evident that any tendency of the garter to expand in such 10 a way as to permit the garter to sag further down on the calf 10 (see Figure 1) will be resisted by the tension in the tension member 8. At the same time, by reason of the unextensible nature of the portion 9 of the band, 15 the tension member 8 cannot be unduly stretched.

The garter is preferably constructed in such a way that the length of the portion 9 can be adjusted as well as the total length of 20 the "girth" of the garter. For this purpose I prefer to provide the band with an inner buckle 11 and an outer buckle 12. The inner buckle 11 is disposed nearer to the pad 2 than the outer buckle 12. I also prefer to employ 25 a buckle 13 disposed quite near the pad 2 which, if desired, may be attached to the pad. This buckle 13 may be fixed on the band 5 but, if desired, may be made adjustable, for which purpose it may be provided 30 with two slots 14 and 15 through which the material of the band 5 may be looped. Between the buckles 13 and 11 the extension 9 of the band lies which is adjacent to the tension member 8 and which limits the degree 35 of tension on the tension member.

The buckle 11 may be employed to adjust the length of the portion 9 and affords means for adjusting the total length of the garter. For this purpose the buckle 11 is provided 40 with two parallel slots 16 and 17 through which the band 5 is passed in a loop 18 passing around the center bar 19 of this buckle. In other words, the extension 9 at its outer end is woven through the buckle so that it 45 passes down through the slot 16 under the bar 19 and thence upwardly through the slot 17 beyond which the band forms an extension 20 the outer end of which forms a loop 21 through the buckle 12 and then passes 50 back in an extension 22 which forms a loop 23 down through the slot 16 under the bar 19 and up through the slot 17 so that the loose end 24 of the band lies between the two 55 extensions 20 and 22. (See Figure 2).

With this described weaving of the band through the buckles, it will be evident that by slipping the buckle 11 toward the left on the extension 9 of the band, the length of this extension 9 between the buckles 11 and 13 can 60 be shortened. The adjustment of the total length of the band 5, however, is independent of the length of the extension 9 by reason of the fact that the length of the loose end 24 can be increased or reduced by adjusting the 65 band at the buckle 11.

The tension member 8 is preferably constructed so that it can be detachably secured on the garter and over the portion 9 of the band. For this purpose the tension member 8 is preferably constructed as indicated in Figure 4, having a metal strip 25 at each end secured to it, and each metal strip is formed with a pair of integral hooks 26. These hooks are adapted to be inserted in the buckles 11 and 13 so that the bills of the hooks 70 overlie the center bars of the buckles, the hooks being inserted through the adjacent slots of the buckles.

In the preferred form of the invention the tension member 8 is formed of elastic webbing 80 (see Figure 1) but, if desired, instead of employing webbing I may employ one or more springs 27 preferably in the form of coils the ends of which are attached to hook plates 28 similar in construction to the plates 25 already described. In this embodiment of the invention the extension 9 of the band 5 between the buckles prevents the springs 85 from coming in contact with the leg and also operates to limit the stretching force to which the springs can be subjected.

If a garter of this general type is constructed entirely of elastic webbing, it gradually loses its strength and must be eventually thrown away. This results usually in the 90 waste of a length of webbing sufficient to form almost the entire length of the girth of the calf where the garter is worn. With my invention, while the tension member 8 is protected from undue stretching which might 95 exceed its elastic limit, whenever the tension member does become worn this does not result in the waste of the entire garter with all the metal fittings and fastenings; it is merely necessary to remove the worn tension member 100 105 110 115 120 125 130 135 140 145 150 155 160 165 170 175 180 185 190 under the action of the constricting force exerted by the tension member 8.

The invention may be applied to a vertical elastic member such as a suspender or hose 5 supporter suspended from a body garment. In the embodiment of the invention shown in Figure 5 it is adapted to be used as a vertical garter at the side of the leg and is especially adapted to be worn by women. This 10 garter consists of a band 29 of substantially unextensible material, a portion of which is overlain by a tension member 30 connected between buckles 31 and 32. This tension member 30 is provided with hook plates 33 15 having hooks 34 similar to the hooks 26 already described. If desired, the lower edge of the garment 35 may be provided with a plurality of snap buttons 36 to which the upper end of the band may be attached by means 20 of similar snap fasteners 37. This enables the garter to be attached in any desired position.

The detachable elastic portion 8 should be constructed at its ends in such a way that its 25 connections to the body of the garter will not become detached when the garter is taken off and thrown down. Any suitable connection to effect this result may be employed, but in order to accomplish this in the type of end 30 fastening I have illustrated, I prefer to provide each end plate 25 with an upwardly projecting flange 25a. When this detachable extensible member is in place these flanges 25a engage the inner edge of the adjacent side bar 35 38 of the corresponding buckle.

In addition to this, the hooks 26 are formed so that each hook presents a shoulder 26a at its back that also engages the adjacent edge of the bar 38. These flanges 25a and the 40 shoulders 26a prevent the hooks from becoming detached unless a considerable rotation takes place about the center bar of the buckle.

The bills of the hooks 26 project over the center bars of the buckles and fit snugly down 45 on the garter band at these points. This is most advantageous in connection with the buckle 11, because the pressure of the hooks against the material of the garter prevents any tendency of the band to slip through the 50 buckle.

One of the advantages of my garter is that the elastic will not come in direct contact with the leg, and consequently it is protected from the moisture of perspiration and also 55 is protected considerably from the heat of the leg. This is very advantageous because it prevents the moisture from deteriorating rubber when that is used as the elastic.

Garters constructed in accordance with my 60 invention can be worn a considerable time and are very economical because the garter can be made practically new again as far as its elasticity is concerned, by removing the old elastic member 8 and substituting a new 65 elastic member.

It is understood that the embodiment of the invention described herein is only one of the many embodiments this invention may take, and I do not wish to be limited in the practice of the invention, nor in the claims, 70 to the particular embodiment set forth.

What I claim is:

1. A garter having a band of substantially unextensible material, a pad attached to one end of the band and having means for attaching the same to the hose, a buckle disposed relatively near to the pad and having the band woven through the same, said band having a loop, an outer buckle in said loop relatively far from the pad, said band being woven back from the outer buckle and looped through the first-named buckle so as to present a loose end beyond the first-named buckle and projecting away from the pad, a resilient tension member connecting the pad and the first-named buckle and overlying the portion of said band between the same, said first-named buckle being adjustable along the band 75 in either direction so as to vary the distance between the pad and the first-named buckle to adjust the limit of tension in the tension member, and said loose end of the band being adjustable through said first-named buckle to adjust the over all length of the band, said outer buckle having means for attaching the 80 same to the pad.

2. A garter having a band of substantially unextensible material, and a pair of buckles carried on said band, and a detachable resilient tension member having hooks at its 85 ends for detachably securing the same in the said buckles and overlying the portion of said band lying between said buckles, said tension member operating to give resiliency to the entire band.

3. A garment supporter having a band of substantially unextensible material with a pair of buckles carried on said band, and a resilient tension member having a metal strap 100 at each end with hook means passing under the adjacent side bar of the buckle and engaging over the outer side of center bar of the buckle.

4. A garter having a band of substantially unextensible material with a pair of buckles carried on said band, and a resilient tension member having a plate at each end with hook means for engaging over the center bar of the corresponding buckle, and having an outwardly extending flange for engaging the inner edge of the adjacent side bar of the buckle.

5. A garment supporter including a band, buckles thereon and a resilient member having a plate at each end, each plate having a pair of hooks for attaching the same to the 115 buckles.

6. A garter having a band of substantially unextensible material and a pair of buckles disposed apart on the said band, one of said buckles being capable of slipping along said 120 125 130

band for adjusting the distance between the buckles, and a detachable tension member detachably engaging said buckles and operating to supply elasticity to the band, the portion of the non-extensible band between the said buckles operating to limit the extension of the resilient means, said band having a loop beyond one of said buckles with an extension passed in a loop around that buckle to enable the total length of the band to be adjusted.

7. A garment supporter, including a band with buckles thereon, and a resilient member having a plate at each end, said plates having hooks for attaching the same to the buckles.

Signed at Los Angeles, California, this 9th day of January, 1930.

SAMUEL N. COULTER.
